UNITED STATES PATENT OFFICE.

CLINTON J. WARREN, OF CHICAGO, ILLINOIS.

MACHINE FOR CORKING BOTTLES.

SPECIFICATION forming part of Letters Patent No. 707,993, dated August 28, 1902.

Original application filed May 16, 1901, Serial No. 60,524. Divided and this application filed December 7, 1901. Serial No. 85,002. (No model.)

To all whom it may concern:

Be it known that I, CLINTON J. WARREN, a citizen of the United States, residing at Chicago, in the county of Cook and State of Illinois, have invented certain new and useful Improvements in Machines for Corking Bottles, of which the following is a specification, reference being had to the accompanying drawings.

10 This invention relates to machines for inserting corks in filled bottles and has for its object to provide means for inserting such corks while the bottles are being moved by an endless carrier, the corking devices being moved for a limited distance parallel with and over the moving carrier and in contact with one of the bottles thereon in which a cork is being inserted and after traveling in such engagement being withdrawn clear of 15 the bottle into which a cork has been inserted and retracted in an opposite direction in order to be in a position to engage and cork a succeeding bottle on such carrier. I accomplish this by the means shown in the 20 drawings and hereinafter specifically described, and that which I claim as new will be set forth in the claims.

The corking devices forming the subject-matter of this application are shown and described in my pending application, Serial No. 60,524, filed May 16, 1901, of which this is a division, in which said application is also shown various other sets of mechanism for operating upon bottles both before and after 35 they are corked, as hereinafter described, and all acting, as does the corking mechanism, while the bottles are being continuously moved forward through the machine.

In the accompanying drawings, Figure 1 is 40 a side elevation. Fig. 2 is a cross-section through the upper portion of the carrier-frame upon which the corking devices are mounted, showing the cork-driving mechanism in elevation and the cork-holding socket in section. The cork-driving devices are 45 represented in their raised position. Fig. 3 is a view similar to that of Fig. 2 with the parts in their lowered position. Fig. 4 is a longitudinal vertical section on line 4-4 of Fig. 3. Fig. 5 is a longitudinal vertical section on 50 line 5-5 of Fig. 2. Fig. 6 is a cross-section

on line 6-6 of Fig. 3, showing in dotted lines the position of the cross-head and attached springs when raised. Fig. 7 is a detail, being a plan view of a section of the endless 55 bottle-carrier and one of the bottle-clamps secured thereon, a portion of the frame for said endless carrier being shown in section; and Fig. 8 is a detail of a portion of the endless bottle-carrier and its frame and the 60 sprocket-wheel that drives such carrier.

Referring to the drawings, in which corresponding parts are indicated by the same reference-numerals, 12 indicates one of a pair of suitable supporting-standards which may 65 be arranged as shown, or a pair of such standards may, if deemed advisable, be located at each end of the machine. Upon these standards is located a framework consisting of two pairs of longitudinal beams 13 14, 13 70 indicating the lower beam, and 14 the upper beam, the upper and lower beams being connected by curved end pieces 15. The upper beams and the lower beams and their connecting end pieces are separated sufficiently 75 to provide a space for a moving carrier to be located between them, such space being clearly indicated in Figs. 2 and 3, where the upper pair of beams 14 are shown in section, and it will be understood that this same 80 space that is shown in these two figures is continued so as to be the same at all points between the pair of lower beams and the pair of upper beams and their connecting ends. The carrier referred to is an endless one and 85 is composed of a number of comparatively heavy blocks 17, each block having ears 18 at its ends, through which pass axles 19, and upon the ends of which axles are journaled 90 rollers 20, these rollers traveling in the grooves 95 16 in the inner faces of the beams 13 14 and their curved end pieces 15.

21 indicates a sprocket-wheel keyed to a shaft 22, mounted in suitable bearings that are secured between the longitudinal beams 95 13 14 near one of the curved ends 15 thereof. 23 indicates another shaft extending across the machine between the longitudinal beams referred to and suitably secured in bearings supported by the framework of the machine. 100 Upon this shaft 23 at one end thereof is secured a pulley-wheel 24, over which a driv-

ing-belt 25 passes. The shaft 23 carries a small gear-wheel 26, which is keyed thereto and which meshes with another and larger gear-wheel 27, which latter gear-wheel is secured upon a projecting end of the shaft 22, whereby upon the rotation of such larger gear-wheel the sprocket-wheel 21 is driven and by its engagement with the axles 19 of the carrier-wheels 20 moves such carrier forward. At the opposite end of the machine from that at which the devices just referred to are located is arranged another and similar sprocket-wheel 28, over which the carrier travels, this sprocket-wheel 28 being located 15 on a shaft 29, journaled in suitable supports secured to the framework.

The outer face of each block 17 is provided with a suitable clamp adapted to receive the base of a bottle and hold such bottle firmly 20 in position, so that it will at all times have its neck end projected outward. The form of clamp shown consists of two similar curved metal bands 30, each portion 30 being bent on itself and at the bent portion secured to 25 the blocks 17 by a screw or other pivot 31. The curvature of each portion of the clamp is such as to adapt it to conform to the curvature of the bottle that is to be held, and it is provided on its inner face, as shown, with 30 two oppositely-arranged cushions 32, one of such cushions being provided for each portion 30. The acting portion of the clamp, as shown, forms nearly a complete circle, the two ends approaching closely to each other, 35 as shown by the dotted lines in Fig. 7, and working back and forth beneath a bracket 33 when pressure is applied to or released from the sides of the clamp. The outer ends of each portion of the clamp bear against the 40 sides of the beams 14, as shown in Fig. 7, with sufficient force to cause the cushions 32 to grasp the bottle firmly, so as to hold it securely whether the bottle be upright or inverted. Suitable means may be provided for 45 automatically inserting the bottles within the clamps and disengaging them therefrom, so as to be discharged from the machine, and means for that purpose are shown and described in my said pending application; but 50 as they form no part of my present invention and so far as my present invention is concerned may be of any suitable character I do not deem it necessary to here show or describe them. It is also to be understood that 55 other forms of clamping devices for holding bottles securely upon the carrier may be employed. In the form of bottle-clamp shown the two portions 30 are adapted to be forced apart at the releasing-point by the action of 60 a curved spring 34, which, as shown in Fig. 7, is secured at one end to one of the parts 30 and bears at its other and free end against the corresponding part 30.

With a series of bottles mounted and suitably held upon the endless carrier and such endless carrier, with the bottles thereon, being continuously driven at a comparatively

slow rate of speed and with the bottles filled and ready to be corked the corking operation is accomplished by the means now to be described.

35 indicates two oppositely-located supports adjustably secured to the outside faces of the two upper longitudinal beams 14, upon each of which supports is secured a sharply-inclined guideway 36, upon which travels a slide 37, having pivotally attached thereto a rod 38, which rod at its opposite end is secured to an eccentric 39 on the shaft 23.

40 indicates upwardly-extending arms 80 formed with or rigidly attached to the slides 37, to the tops of which arms is bolted a cross-head 41, having an enlarged central head 42, through which head passes a plunger 43, that is preferably screw-threaded into said head 85 42, so that by means of the screw-thread the plunger may be accurately adjusted with relation to the part with which it co-operates. This central head 42 and the plunger carried thereby are arranged directly over the longitudinal center of the bottle-carrier, which, as before described, is made up of the blocks 17, so that when the device is operated the plunger will be in direct line with the necks of the bottles clamped to and moving with said 95 carrier. 44 indicates a second cross-head, that has its ends confined in vertical guideways formed in the inner faces of the upwardly-extending arms 40, which guideways are indicated in Figs. 2 and 3 by dotted lines. 100 Such second cross-head 44 is also provided with a central enlargement or head 45, in which is formed a socket 46 of a size adapted to receive a cork of the character employed for the bottles being operated upon. As 105 shown in Fig. 8, this socket is open at one side, and through this side opening the corks are forced.

47 indicates two brackets, one of such brackets extending out from each support 35 110 about at the upper end of the guide 36 and being bent sufficiently to bring over the middle of the machine a longitudinally-extending tubular socket 48, which is supported on said brackets. 49 indicates a plunger movable within said socket, said plunger being provided with a rod 50, around which is a coiled spring 51, that tends to force the plunger outward. To the outer end of the plunger-rod 50 is pivoted a jointed or toggle lever 115 52, the joint being indicated by 53 and the pivotal point in the long member of the lever by 54, the pivoting of the lever being to an extension 55, formed with or secured to the upper part of the socket 48.

56 indicates a cord or other flexible connection secured to the long member of the lever 52 near its upper and free end and secured at its other end to a short rigid arm or hook 57, projecting from the cross-head 41.

58 indicates a hopper adapted to contain a supply of corks for the bottles, from the lower end of which hopper extends a tube 59, the open lower end of which communicates

with the interior of the tubular socket 48, as clearly shown in Fig. 4. This tube is preferably slotted, as shown, in order that such slots may afford means of determining whether the corks are properly feeding downward or are becoming clogged therein and if clogged may be straightened out by means of a wire or rod inserted through the slots.

5 60 indicates short arms attached to the lower face of the cross-head 44, near opposite ends thereof, each of said arms carrying at its lower end a roller 61, that bears upon a track 62, attached in any suitable manner to the inner faces of the supports 35. Each of these tracks at one end is slightly higher than at the other end, and the passage from one level of the tracks to another is by a rather short sharp incline, as shown clearly in Fig. 4 and also as indicated by dotted lines in Fig. 5.

10 63 indicates two pairs of flat steel springs, each spring being firmly secured in place at its upper end in any suitable manner to the cross-head 41, a pair of such springs being located about midway between the enlarged central head 42 and one end of the cross-head. Each pair of these springs has a tendency to bear against the lower cross-head 44, and at a point opposite the lower edge of said cross-head 44, when the other cross-head is lowered, as shown in Fig. 3, the springs are each provided with a bend 64, forming shoulders that project under the lower face of the cross-head 44 when the other cross-head 41 is in its lowest position. By thus providing these 15 shoulders in the springs the cross-head 44 is firmly held between them and raised for a short distance when the cross-head 41 is raised.

20 The operation of the machine is as follows: With the bottle-carrier being continuously driven at a uniform rate of speed and with a series of bottles securely clamped thereon by the clamps shown or by any other suitable means and the bottles having been filled by the filling mechanism shown in my said pending application or by some other means it is evident that the turning of the shaft 23, on which the eccentric 39 is secured, will cause a reciprocation of the rod 38, attached thereto, and upon the backward movement of such rod the slide 37 on the guide 36 will move upward on said guide and will of course, in view of the guide 36 being inclined, move in the reverse direction to the travel of the bottles on the carrier. The upright arms 40 and attached cross-heads being connected to this slide will of course move with it, and at the completion of the upward movement they are in the position shown in Fig. 5. At just about the time of the completion of their upward movement the projection 57 on the cross-head 41 will strike the free end of the long arm of the lever 52 with sufficient force to turn it on its pivot 54, causing it to bend 25 at its joint 53, which will allow the coiled spring 51 to force the plunger 49 forward, forcing out from in front of it a cork which had previously dropped from the tube 59, causing such cork to enter the upper end of the socket 46, when it will immediately settle 30 into the tapered lower portion of such socket. The action of the eccentric through the rod 38 then forces the slide 37 downward on its guide 36, and after it has traveled but a very short distance the rollers 61, carried by the 35 arms 60, that are attached to the under face of the lower cross-head 44, descend the inclined portion of the oppositely-located tracks 62, which gives a quick downward motion to the lower cross-head. This action settles the 40 central portion 45 of the cross-head 44 firmly down upon the head of a filled bottle, upon which it bears with considerable weight. The central portion of the under face of this cross-head 44 is concave around the cork-holding 45 socket, as clearly shown in Fig. 4, and this aids in securing the alinement of the cork-holding socket with the neck of the bottle. Further downward movement of the cross-head 44 is prevented; but the upper cross-head 41 continues to descend, with the ends of the cross-head 44 sliding in the grooves in the inner faces of the upright arms 40. The continued downward movement of the cross-head 41 of course carries the plunger 49 with 50 considerable force against the cork in the socket 46, forcing the cork through such socket into the neck of the bottle. The cross-heads move along with the movement of the bottle being corked, owing to the inclined arrangement of the slide 37 and its guide 36. As the cross-head 41 moves downward and farther from the cork-delivering tube 59, which latter tube is stationary, the other flexible connection 56 is of course drawn taut and 55 acts to pull back the lever 52 sufficiently to withdraw the plunger 49, which withdrawal allows another cork to drop from the tube 59 into the tubular socket and in front of said plunger. When drawn back, the joint 53 in the lever 52 will lock the two parts of such lever until the lever is again tripped by the projection 57, as before explained. As the slide 37 starts again on its upward movement on the guide 36 it is necessary that the lower 60 cross-head 44 be instantly released from contact with the bottle just corked, and this is effected by means of the two pairs of broad flatsprings 63, previously referred to. These springs are made quite strong and spring toward each other with considerable force. As the slide starts upward it of course carries the upright arms 40 and the attached cross-head 41, to which latter cross-head the springs are attached at their upper ends, their lower ends 65 being free and bent in toward each other. These springs having the decided bends 64 in them, which bends at this time are immediately under the lower edges of the cross-head 44, enable said cross-heads 44 to be immediately lifted by the springs, so as not to interfere with the forward movement of the now-corked bottle, and such springs will so support the cross-head until the rollers 61 strike

the incline of the track 62 and ascend such incline. The rollers will then come in contact with strips 65, which, as shown, project over the track 62, and the contact of the 5 rollers with such strips will prevent the cross-head 44 from rising further, and as the other cross-head 41 continues to rise the springs 63 will of course be drawn up with them and as they are drawn up will be forced outward, so 10 that the bent portions or shoulders 64 can pass the lower cross-head.

In Fig. 1 I have shown the eccentric-rod 38 as being divided into two parts which are joined together by a vertical arm, (see Fig. 1,) 15 to the upper end of which arm the forward portion of the rod 38 is pivoted. I have so shown it to make the drawing correspond more nearly with the construction shown in my said pending application; but it is evident, of 20 course, that a single continuous eccentric-rod may be employed.

By my invention I provide an accurately-working set of devices by which corks can be quickly and accurately driven into the necks 25 of filled bottles while said bottles are being continuously moved, which method of corking bottles is one of especially great value when used in connection with other devices or sets of devices mounted upon the same 30 frame, as shown and described in my said pending application, where said other devices or sets of devices also act to operate both before and after the corking operation upon the same bottles while they are being moved 35 through the machine.

That which I claim as my invention, and desire to secure by Letters Patent, is—

1. In a bottle-corking machine, the combination with a movable carrier adapted to receive and hold a series of bottles with their neck ends projected, of means for continuously moving said carrier, cork-inserting devices adapted to insert corks in successive bottles of said moving series, means for causing said inserting devices to move for a limited distance alongside of the moving series of bottles, and means for retracting said inserting devices in an opposite direction from that of the movement of the carrier, substantially as specified.

2. In a bottle-corking machine, the combination with a movable carrier adapted to receive and hold a series of bottles with their neck ends projected, of means for continuously moving said carrier, cork-inserting devices adapted to insert corks in successive bottles of said moving series, means for causing said inserting devices to move for a limited distance alongside of the moving series of bottles, means for retracting said inserting devices in an opposite direction to that of the movement of the carrier, and means for advancing a cork in position to be acted upon by said inserting devices after each retracting movement, substantially as specified.

3. The combination with a carrier adapted to receive and hold a bottle thereon with the

neck end projected, of means for continuously moving the carrier, a cork-carrying device, means for moving said cork-carrying device a limited distance alongside of the bottle and returning it to its normal position, and means for forcing a cork from said cork-carrying device into the neck of the moving bottle.

4. The combination with a carrier adapted to receive and hold a bottle thereon with its neck end projected, of means for moving the carrier, a cork-carrying device, means for giving said cork-carrying device a reciprocating motion over and in the line of travel of the bottle, and at the same time a descending and ascending movement to bring said cork-carrying device into contact with the top of the bottle and to retract it therefrom, and means for forcing a cork from said cork-carrying device into the bottle while in contact therewith and while said bottle is being moved with its carrier, substantially as described.

5. The combination with a frame, a carrier supported thereby and adapted to receive and hold a bottle with its neck end projected, means for moving the carrier, a cross-head suitably supported above said frame, a plunger carried thereby, and a second cross-head movable vertically in the supports of the first-named cross-head and provided with means for holding a cork, of means for forcing the cross-head carrying the cork down upon the top of the moving bottle, means for forcing down the other cross-head to bring the plunger carried thereby into contact with the cork in the cork-carrying cross-head and thereby force such cork into the neck of the moving bottle, and means for withdrawing said devices after the cork has been forced into the bottle, substantially as specified.

6. The combination with a frame, a carrier supported thereby and adapted to receive and hold a bottle with its neck end projected, means for moving the carrier, a cross-head suitably supported above said frame, a plunger carried thereby, and a second cross-head movable vertically in the supports of the first-named cross-head and provided with means for holding a cork, of means for forcing the cross-head carrying the cork down upon the top of the moving bottle, means for forcing down the other cross-head to bring the plunger carried thereby into contact with the cork in the cork-carrying cross-head and thereby force such cork into the neck of the moving bottle, means for withdrawing said devices after the cork has been forced into the bottle, and means for automatically supplying said cork-carrying cross-head with another cork after such withdrawal, substantially as specified.

7. The combination with a carrier adapted to receive and hold a bottle thereon with its neck end projected, of means for moving the carrier, a cork-carrying device, means for giving said cork-carrying device a reciprocating motion over and in the line of travel of

the bottle and a descending and ascending movement to bring said cork-carrying device into contact with the top of the bottle and to retract it therefrom, means for forcing a cork from said cork-carrying device into the bottle while in contact therewith and while said bottle is being moved with its carrier, a receptacle for containing a quantity of corks, and means for feeding from such receptacle a single cork to the cork-carrying device each time that said cork-carrying device is drawn to the limit of its backward and upward motion, substantially as specified.

8. The combination with a carrier adapted to receive and hold a bottle thereon with its neck end projected, of means for moving the carrier, a cork-carrying device, means for giving said cork-carrying device a reciprocating motion over and in the line of travel of the bottle and a descending and ascending movement to bring said cork-carrying device into contact with the top of the bottle and to retract it therefrom, means for forcing a cork from said cork-carrying device into the bottle while in contact therewith and while said bottle is being moved with its carrier, a receptacle for containing a quantity of corks, means for feeding from said receptacle a single cork to the movable cork-carrying device each time that said cork-carrying device is brought to the limit of its upward and rearward movement, and means carried by said movable cork-carrying device for setting in operation the means for forcing a cork from the receptacle containing a supply of corks into the movable cork-carrier, substantially as specified.

9. The combination with a carrier adapted to receive and hold a bottle thereon with its neck end projected, of means for moving the carrier, a cork-carrying device, means for giving said cork-carrying device a reciprocating motion over and in the line of travel of the bottle and a descending and ascending movement to bring said cork-carrying device into contact with the top of the bottle and to retract it therefrom, means for forcing a cork from said cork-carrying device into the bottle while in contact therewith and while said

bottle is being moved with its carrier, a receptacle for containing a quantity of corks, means for feeding from said receptacle a single cork to the movable cork-carrying device each time that said cork-carrying device is brought to the limit of its backward and rearward movement, means connected with said movable cork-carrying device for setting in operation the means for forcing a cork from the said receptacle into the movable cork-carrier, and a connection between said movable cork-carrier and the means for supplying corks from the receptacle whereby upon the downward and forward movement of the cork-carrier a single cork will be dropped into position and the parts for ejecting corks locked until the next upward and rearward movement of the cork-carrier has been effected, substantially as specified.

10. The combination with a carrier adapted to receive and hold a bottle thereon with its neck end projected, of means for moving the carrier, a cork-carrying device, means for giving said cork-carrying device a reciprocating motion over and in the line of travel of the bottle, and at the same time a descending and ascending movement to bring said cork-carrying device over and in line with the top of the bottle and to retract it therefrom, a stationary receptacle for containing a supply of corks, a tube connected with said receptacle at its upper end and at its lower end with a chamber, a plunger within said chamber adapted to be drawn back to permit a cork from said tube to be dropped in front of said plunger, a connection between said cork-carrier and said plunger whereby said plunger is retracted as the cork-carrier moves away from it, means connected with said cork-carrier for releasing said plunger from its retracted position when said cork-carrier is at its upper and rearward position, and means for forcing said plunger forward to move the cork in front of it into said cork-carrier, substantially as specified.

CLINTON J. WARREN.
